COVERING MATERIAL

John A. Topping, Bronxville, N. Y.

Application December 8, 1933, Serial No. 701,477

10 Claims. (Cl. 108—7)

This invention relates to covering elements and more particularly to covering elements for surfaces exposed to the weather, especially those in the form of strips simulating shingles. The invention also relates to the process of making such elements.

Shingle strips with shingle simulating tabs separated by spaces or notches are in common use. Strips upon which are formed tabs which are separated by recesses having an outline complementary to the tab also have been used. An example of such a strip is one formed with a tab in the shape of a half hexagon in which the recess is also a half hexagon. When two such strips are laid in an overlapping arrangement a hexagon motif may be formed in the roof or assembly upon the surface to be covered. In general, the assemblies of such strips upon the roof or upon the surface to be covered produce a regular outline of the motif, such as the hexagon, formed by regularly placing the tabs of one strip with respect to the recesses of a strip to be overlapped.

The present invention provides a covering element or strip formed with tabs separated by a recess. The outline of the tab is such that it is similar to that of the recess between the tabs. In the preferred embodiment of my invention the form of the outline of the tab is such that while being similar to that of the recess it is not complementary thereto. My invention, however, is not limited to elements or strips in which the tabs have an outline not complementary to that of the recess but includes elements or strips provided with tabs having a form of outline which is complementary to that of the recess. In either case the form of the edge to be exposed of the tab and of the inner edge of the recess are similar or alike and are so placed with respect to the body of the strip that when strips of like kind or of different kinds as to the complementary relation of the tabs and recesses are assembled upon a surface or to form a roof, unusual designs and motifs may be secured which are the result of the mechanical form of the strip and of the mechanical relation of the outline of the tab or of the recess with respect to the body of the strip and also of the mutual relationship of said outlines of tabs and recesses.

Moreover, as will be hereafter described, according to my invention there may be formed two strips of complementary outline, one with respect to the other in the edges to be exposed thereof, each of which strips is provided with tabs separated by recesses or spaces. In each

strip the tabs and recesses themselves may be complementary to each other or may be non-complementary to each other. However, as a feature of the invention they have similar outlines. There thus may be provided, according to my invention, a pair of strips which may be cut from a sheet of material without waste according to the process to be described and each of which may be used to produce a number of novel assemblies upon the surface to be covered, having novel symmetrical or unsymmetrical outline of the motifs produced and which also, when used together, may produce modifications of the effect of the exposed edge of the single tabs or of the single recesses, as will hereafter be described.

My invention in its preferred embodiment relates to covering elements having tabs which are not complementary to the spaces between the tabs but which have the edges thereof formed with an outline similar to that of the recess or spaces between the tabs. While the invention broadly or in its preferred embodiment, is not limited to a particular form of the outline of the tab and of the recess, I prefer to form the outer edge of the tab with an outline which, when viewed with respect to the body of the element, is the same or similar to the outline of the inner edge of the recess when viewed with respect to the body of the strip. Thus in a particular embodiment I may use a serrated outer edge for the tab and a serrated inner edge for the recess, each of these edges having the same or similar outline and similar placement with respect to the body of the element of the lines forming the points and notches of the serration. Thus I may accomplish the formation of the recess with an outline which is not complementary to that of the tab but is of similar or like outline thereto.

When utilizing such a form of the edge of the recess and of the tab I may cut from a sheet two strips, each of which has the tabs thereof complementary to the recesses of the other strip and each of which may have the tabs thereof complementary to or non-complementary to the recesses between its own tabs. When the tabs and recesses of each strip have outlines which are similar but not complementary to each other, two strips may be produced at the same time in so cutting the sheet, which strips are not alike but both of which have tabs which are of similar outline and recesses which are of similar outline.

The invention will be more clearly understood from the following description taken in connection with the drawings of which

Figure 1 shows a sheet cut in outlines to produce the covering elements of the invention.

Figure 2 shows an element having the typical form of the invention.

5 Figure 3 shows an element complementary to that of Figure 2.

Figure 4 shows a modified form of the element of Figure 2.

10 Figure 5 shows a modified form of the element of Figure 3.

Figure 6 shows an assembly using the elements of Figures 2 and 3.

15 Figure 7 shows a sheet cut in outlines to produce complementary tabs and spaces in each element.

Figure 8 shows a single element of the type produced by the method of cutting illustrated in Figure 7.

20 Figure 9 shows an assembly of the elements of Figure 7.

Figure 10 shows a sheet cut in outlines to produce elements having the tabs and spaces thereof complementary to each, said element having outlines similar to but not complementary to the elements of Figures 7 and 8.

25 Figure 11 shows a single element of the type produced by the method of Figure 10.

Figure 12 shows an assembly of the elements of Figure 11.

30 Figure 13 shows an assembly of the elements of Figures 2 and 3 in varied arrangement.

Figure 14 shows as a further modification an assembly of the elements of Figures 2 and 3.

35 In Figure 1 is shown diagrammatically a sheet $\mathfrak{f}$ of indefinite length having a width equal to the depth of one element from the outer edge of its tab to the opposite longitudinal edge of the element plus the depth of a complementary element from the inner edge of its recess to its opposite 40 longitudinal edge. In full lines are shown the elements illustrated in Figures 2 and 3. The element shown in Figure 2 is marked 2 in Figure 1 and the element shown in Figure 3 is marked 3 in Figure 1. In the particular embodiment of 45 the invention as illustrated in Figures 2 and 3 the element 2 has its longitudinal dimension extending between the lines 5 and 6, which lines extend transversely across the element and transversely to the length of the sheet $\mathfrak{f}$ from which 50 the element is cut. Correspondingly, the element 3 has its longitudinal dimension extending between the lines 9 and 10, which lines extend transversely of the element and of the sheet from which the element is cut.

55 In the particular embodiment illustrated in Figure 2, the element is provided with tabs 12 and 13 separated by a space or recess having a width equal to the width of the tabs but the invention is not limited to tabs and recesses of equal width. 60 Adjacent the tabs at the ends of the elements are recesses which are equal in longitudinal dimension to one-half the width of the space between the tabs 12 and 13. In this particular embodiment the tabs are formed with straight lines 65 14, 15, 16 and 17 extending transversely of the longitudinal dimension of the element and connecting the edges 18 and 19 of said tabs with the inner edges 22, 23 and 24 of the recesses. By using a straight line for these transverse edges I 70 may more easily separate the complementary strips as they are cut from the sheet. However, other forms for this transverse line may be used within the scope of the invention. In the embodiment illustrated the edge 18 of the tab 12 is 75 formed in serrated outline having the portions 30,

31, 32 and 33 providing points 34, 35 and 36. The inner edge 23 of the recess formed between the tabs 12 and 13 is of similar serrated outline composed of the parts 40, 41, 42 and 43. The inner edge 22 of the recess at the lefthand end of the 5 element is formed with two portions corresponding to the portions 42 and 43 of the edge 23 and the inner edge 24 of the recess at the righthand edge of the element is formed with portions 40 and 41 10 corresponding to the portions 40 and 41 of the edge 23. It will be noted from Figure 2 that the outline provided by the edges 22, 23 and 24 is similar to the outline provided by the edges 18 and 19 of the tabs 12 and 13.

Moreover, it will be noted that with respect to 15 the body of the element the outlines of the edges 18 and 19 of the tabs 12 and 13 and the edge 23 of the recess are similarly placed, that is, the edge 23 of the recess provides notches between the portions 40 and 41 and between the portions 20 42 and 43, which correspond with the notches between the portions 30 and 31 and between the portions 32 and 33 of the edges 18 and 19 of the tabs. These edges of the tabs and of the recess 25 may be said to be similarly formed and of similar shape and provide outlines of two different portions of the body of the element which are similar or alike and are similarly placed with respect to the body of the strip.

It will also be noted, however, in the particular 30 embodiment of Figure 2 that the outline provided by the tabs is not complementary to the outline provided in the recess, that is to say, it is not possible to fit the tab 12 or the tab 13 into the recess between the tabs so that the outline of the edge 18 or of the edge 19 will fit to the outline of the edge 23 of the recess. The points 34, 35 and 36 of the tabs will meet the corners 44 and 46 and the point 45 of the edge 23 and the notches between the portions of the outlines will leave open 40 spaces. By such a form of outline for the edges of the tabs and of the inner edges of the recesses there thus is provided a strip having tabs which are separated by a recess or space or which alternate with recesses, the tabs being non-complementary to the spaces.

The element shown in Figure 3 is provided with tabs 52 and 53 having transversely extending edges 54, 55, 56 and 57. These edges are formed as straight lines in this embodiment. 50 Between the tabs 52 and 53 and at either end of the strip are formed recesses having inner edges 62, 63 and 64.

The tabs 52 and 53 are formed in serrated outlines 55 58 and 59 which may be said to be inverted from that provided by the edges 18 and 19 of the tabs of the strip of Figure 2. The edge 58 thus is formed by the portions 70, 71, 72 and 73 forming corners 74 and 75 and points 76 and 77. The edge 63 of the recess between 60 the tabs 52 and 53 is formed by portions 80, 81, 82 and 83 resulting in points 84 and 85. Similarly the edges 62 and 64 of the recesses at the ends of the element are formed by portions 82 65 and 83 for the lefthand recess and portions 80 and 81 for the righthand recess corresponding to the respectively numbered portions of the edge 63.

Upon inspection of Figure 3 it will be noted 70 that the edges 58 and 59 of the tabs 52 and 53 have a similar outline to the inner edges of the recesses and are similarly formed with respect to the body of the element in like manner to that described in connection with Figure 2. It will also be noted that the edges 58 and 59 of said 75

tabs 52 and 53 are not complementary to the edge 63 of the recess and that if one of said tabs were inserted in the recess the points 76 and 77 of the tab would meet the points 84 and 85 of the edge of the recess, leaving open the spaces between the notches. Thus the edge of the tab is not complementary to the edge of the recess although the outline utilized for the edge of the tab is the same or similar to that of the recess.

By reference now to Figure 1 and by reference to corresponding reference numerals which are the same in Figure 1 as those used in Figures 2 and 3, it will be noted that the element 2 of Figure 2 has such an outline as to fit to the outline of the element of Figure 3. The edge 18 of the tab 12 and the edge 19 of the tab 13 fits to the edges 64 and 63 of the recesses of the element of Figure 3. Correspondingly the edge 58 of the tab 52 and the edge 59 of the tab 53 fit to the edges 24 and 23 of the recess of the element 2. As shown in Figure 1 in full lines, the edges 6 and 9 are offset longitudinally of the sheet 1 a distance corresponding substantially to the width 25 of the tab or of the space. Similarly, the edges 5 and 10 are offset. By cutting the elements from the sheets along the lines 5 and 6 and 9 and 10 both strips are formed with recesses at the ends of the strips, which has certain advantages hereafter to be described. Thus it may be seen that by the method of cutting shown in Figure 1 a pair of elements is provided, each of which has an outline of the edge to be exposed thereof which is complementary to that of the other element but which, as described above, have tabs and recesses which are not complementary.

In order to produce the elements which have been described in connection with Figures 1, 2 and 3 I form the serrated outline, or other outlines having the character which will produce tabs and recesses in each element which are not complementary to each other but which will in each pair of elements form the tabs with outlines complementary to the recesses of those of the other element, by cutting adjacent the center of the sheet 1 the line 90 forming the serrations laterally offset in different portions to produce the edges 18 and 19 and 58 and 59 of the tabs and the edges 22, 23 and 24 and 62, 63 and 64 of the recesses, as well as to produce the connecting edges 14, 15, 16 and 17 of one element and the connecting lines 54, 55, 56 and 57 of the other element. Thus the line 90 of Figure 1 is composed of the various portions which have been described in connection with Figures 2 and 3, some of the numerals from which are indicated in Figure 1.

It will be noted from Figure 1 that the outline 90 while having an apparently general symmetrical relationship to the center line of the sheet 1 is not symmetrical about said center line. The notches of one tab form the points of the recess of the other element and the points of the tabs of one element form the notches of the recess of the other element. Thus, as may be seen from Figure 1, when viewed in one direction the points of the outline project all in one direction, that is, toward one side of the sheet 1 and the notches between said points all project inwardly toward the other side of the sheet 1. However, within the scope of my invention I may use other forms of outlines for the edge of the tab and for the inner edge of the recess which, while the tab of one strip is complementary to

the recess of the other, said outlines are such that said tab is not complementary to the recess in its own strip. It also will be noted that in the elements shown in Figures 1 to 5 inclusive the outlines of the tabs or of the recesses are 5 symmetrical about lines transversely of the longitudinal dimension of the element. However, within the scope of my invention these outlines may be unsymmetrical about such a transverse line while maintaining the general complementary form in the two elements formed in the sheet 1 and while maintaining the non-complementary form of the tabs and recess in each element.

An important feature of my invention consists 15 in so cutting the sheet 1 as illustrated in Figure 1 that the distance from the outline of the central cut, which severs the sheet into the two elements, produces two complementary elements which may be laid adjacent each other endwise in a course 20 with the rear or overlapped edges of the two elements in line in order to modify the motifs produced by the assemblies referred to above. For example, the strips illustrated in Figures 1, 2 and 3 may be formed with the serrated edge having 25 the portions 30—31, etc. and 70—71, etc. extending at such angles that the meeting point of said two lines in each case is offset laterally $\frac{1}{2}$ " from the other ends of said lines 30—31, etc. and 70—71, etc. In other words, the points 34, 35 and 30 36 extend $\frac{1}{2}$ " beyond the inner corners of the notches between these points, and the points 76 and 77 extend $\frac{1}{2}$ " beyond the corners 74 and 75 and beyond the inner corner of the notch between said points 76 and 77. It will be seen 35 from the above description in connection with Figure 1 that the lines 14, 15, 16 and 17 are of equal length with the lines 54, 55, 56 and 57. For example, the length of these lines forming the side edges of the tabs and of the recesses may 40 be 4".

If now, for example, the distance X from the corners 44 and 46 of the element 2 to the rear or overlapped edge 20 of said element is $7\frac{1}{2}$ " and the distance Y from the corners 88 and 89 adjacent 45 the sides of the recess of the element 3 to the rear edge to be overlapped 50 of said element is 7", then, if the element 3 is laid endwise adjacent to the sides of the recess of the element 3 to the rear edge to be overlapped 50 of said element is 50 7", then, if the element 3 is laid endwise adjacent in a course to element 2 with the edges 9 and 6 abutting and with the back edges 50 and 20 50 aligned in the direction of the course, lines 41 and 82 respectively of the elements 2 and 3 will not fall in line but one will be offset $\frac{1}{2}$ " with respect to the other in a direction transversely of the course. The distance from the edges 20 and 55 50 to the outermost point of the outline of the recess in each strip will be $7\frac{1}{2}$ " and the distance Z from said overlapped edges 20 and 50 to the outermost point of the edge of the tab in each strip will be $11\frac{1}{2}$ ". These dimensions are merely 60 examples and other dimensions may be used without departing from the invention. Moreover, by providing a suitable laying mark on each element at an equal distance in the element 2 and in the element 3 respectively from the edges 20 and 50 65 the degree of overlap of the courses may be determined while still providing for producing varied effects in the motifs as will be hereafter described.

Thus, according to one feature of my invention 70 I provide two complementary elements or strips which may have the tabs and recesses of each element formed in outlines which may be complementary to each other or which may be non-complementary to each other as described above, 75

and which elements have a difference in their transverse dimension with respect to the distance from the edge of the tab or of the recess to the edge to be overlapped of the element, so that a 5 means is provided for securing a variety of symmetrical and defined novel motifs in the assembly of said elements while also providing for assembling the elements to produce irregular motifs irregularly arranged, as will be hereafter 10 described.

The elements shown in Figures 4 and 5 correspond respectively to the elements shown in Figures 2 and 3 and have forms of tabs and recesses respectively like those shown in Figures 2 and 3. 15 However, each of the elements of Figures 4 and 5 have two recesses separating three tabs. Such forms of the elements, as will be understood by reference to Figure 1, may be produced by cutting the sheet 1 transversely of the length thereof 20 along the dotted lines 95 and 96 to produce the element of Figure 4 and along dotted lines 99 and 100 to produce the element of Figure 5.

It will be noted that the lines 95 and 96 and 99 and 100 are so positioned as to cut in two an 25 otherwise complete tab formed by the line 90. This may in some cases make such a form of the elements unsuitable for protection against the weather due to the possibility of leakage through the joint necessarily formed between elements 30 abutting endwise. In assemblies such as that shown in Figure 14, however, or where the assembled covering need not be water tight or other means are used for water tightness, the forms shown in Figures 4 and 5 may be used to provide 35 variations of design. When the forms of the elements shown in Figures 2 and 3 are used the end joints become covered with tabs as may be seen from the assembly figures, for example Figure 6, and the covering, therefore, is made 40 water tight.

The above description for the most part has referred to the embodiment of the invention in which two complementary elements or strips 2 and 3 are formed each having the tabs thereof 45 similar to but of non-complementary outline to the recesses of the respective strips. In Figure 7 the sheet 1 is shown cut with the outline 109, which resembles the outline 90 of Figure 1. However, in the two strips 108 formed by the cut having the outline 109, the tabs 110 of the strips 108 50 have their edges 112 similar and complementary to the edge 114 of the recess between said tabs 110. An individual element 108 formed as shown in Figure 7 is illustrated in Figure 8. It will be 55 noted that not only both elements are alike and have their tabs complementary to the spaces between the tabs but that the edge 112 of the tab, while of similar form to the edge 114 of the recess, is not formed in like relation but in inverted relation to the body of the element as is the edge 114 of the recess.

While in some cases I may form the strips on either side of the line 109 with different transverse widths from the line 109 to the edge to be 60 overlapped 120, in order to obtain different forms of the motifs which I desire to produce in the assemblies, I preferably make the distances from the outline 109 to said edge 120 in both strips at either side of said line 109 the same. Thus the 65 edges 105 and 106 of the strip 108 are of the same length and like points of the serrations are at equal distances from the edge 120 in the two strips produced by the cut 109.

In Figure 10 the sheet 1 is similarly cut in an 70 outline 119 to produce tabs 113 of serrated out-

line 115 and complementary to a serrated outline 117 of the recess between the tabs 113. A single element 111 of the form produced by the cut 119 is shown in Figure 11 and the elements 111 on either side of the cut 119 each have their 75 tabs of the same outline and complementary to the space between the tabs on each element. It will be seen that the outline 119 is a modification of the outline 109 as shown in Figure 7 and that the form of strip 111 is similar but not complementary to the form of strip illustrated in Figure 8. As has been stated above in connection with Figures 7 and 8 the strips formed as in Figure 10 may be made of equal transverse width or if desired to produce different effects, 10 may be made of unequal widths. In some cases I may make the strips of such width with respect to those of Figures 7 and 8 that the length of the edges 116 and 118 are the same as the length of the edges 105 and 106 of the strip of Figure 8. 15 In such case it will be seen that when a strip as shown in Figure 8 is laid endwise adjacent in a course to a strip as shown in Figure 11 with, for example, the edge 106 of the strip of Figure 8 abutting against the edge 116 of the strip of Figure 11, the portions of the serration in the adjacent strips which are adjacent the end edges thereof will fall in line and a serrated outline of peculiar form will be produced for the recess formed between a tab 112 of the strip 108 and the tab 113 of the strip 111. When the strips of Figures 8 and 11 are made with the transverse width, from the rear edges 120 and 122 to the outermost point of the tabs, the same, then if strips 108 and 111 are laid endwise adjacent in a 20 course said positions of the serrations will not fall in line but the points of the strip 111 will fall below those of the strip 108. 25

Thus within the scope of my invention I may produce strips which have tabs complementary 30 to the recesses or spaces between the tabs and strips which are of like form and are cut complementary to each other. However, I also may form strips which have their tabs complementary to the recesses between the tabs and which, being formed in pairs and being of like form in 35 said pairs, are not complementary to similarly formed strips having similar outlines. All the various forms of complementary tabs and recesses and non-complementary tabs and recesses and of strips which are complementary to each other and those which are non-complementary to each other, as has been described above, are within the scope of my invention and are useful in the assemblies hereafter to be described in producing the motifs and designs in great variety. It is to be noted that this invention resides not in the design forms themselves and moreover that the possibility of producing the different and varied designs with the same 45 elements resides not alone in a mere design form for the edge of the strip itself, but in the mechanical relation of said form of the edge of the tab and of the recess in relation to each other and in their relation to the body of the element. 50

Also according to my invention, I provide a process of producing an element having a tab and a recess, the outline of the tab being similar to that of the recess but non-complementary thereto. I also provide a process for producing a pair 55 of strips which are complementary in their outlines and are provided with tabs and recesses between the tabs, each of the tabs having an outline similar to but non-complementary to that of the recess in the strip of which it is a part. 60

Moreover, I provide a process of producing elements which may be laid in overlapping arrangement and which have configurations of the tabs and the spaces between the tabs which make possible new effects in an assembly of the element in overlapping arrangement as well as a process of producing pairs of such strips by which variations may be made in the effects produced by such assemblies.

10 In the illustrations described above the transverse edges of the tabs, for example, the edges 14, 15, 16 and 17 and edges 54, 55, 56 and 57, have been formed as straight lines. While in some cases I may use other outlines for these 15 edges and also may form the edges with the lines extending at angles to the longitudinal dimension of the strip other than a right angle, in general I prefer to utilize a form for this edge which is of simple outline in order that in cutting 20 the complementary strips I may easily separate one strip from the other when said strips are severed from the sheet by the cut of serrated outline adjacent the center of the sheet. When outlines of serrated form, or others having angles 25 and indentations, are used it has been found difficult easily to separate one strip on one side of the cut from that on the other side.

In Figure 6 is shown an assembly of the elements 2 and 3 illustrated in Figures 2 and 3, the 30 element 2 of Figure 2 being shown in the topmost course illustrated and the element 3 of Figure 3 being shown therebeneath and overlapped by the element 2. The assembly of Figure 6 shows alternate courses of the elements 2 and 3. It will 35 be noted that the edges 18 and 19 of the tabs 12 and 13 of the element 2 are placed adjacent the edges 62, 63 and 64 as the case may be of the element 3 in the course therebeneath; also that the edges 58 and 59 of the tabs 52 and 53 of the element 3 are placed adjacent the edges 22, 23 and 24 of the recess of the element 2.

As has been mentioned above, by suitably located laying marks 25 and 65 respectively in the elements 2 and 3, a suitable amount of overlap 45 or head lap of one course with respect to the other may be obtained and the advantage also may be obtained of uniformly laying the strips in the courses with respect to the subjacent course. For example, when the strips or elements of Figures 2 and 3 are laid as shown in Figure 6 the courses may have a 4½" spacing as measured 50 between the edges 20 and 50. When the rear edge 20 of an element 2 is laid at a distance, for example 4½" from the edge 50 of a subjacent element 3, for strips having the particular dimension given, a minimum head lap of 2½" is provided. It will also be seen that when an edge 50 of an element 3 is placed at a distance of 4½" from the edge 20 of the subjacent element a similar head 55 lap is provided. Moreover, it will be clear from inspection of Figure 6 that this mechanical construction makes possible a water tight covering while obtaining variations of the form of the motif produced by laying the elements in the 60 overlapping courses as illustrated in Figure 6, two different motifs and two modifications of edge forms being secured.

It will be seen that adjacent the edges 18 and 19 of the strip 2 are formed small diamonds by 65 the adjacent relationship of said edges 18 and 19 to the edges 62, 63 and 64 of the recesses of the subjacent strip. Also it will be seen from Figure 6 that the edges 58 and 59 of the strip 3 form a centrally positioned diamond and two half diamonds at either side thereof by the adjacent re-

lationship of the edges 58 and 59 to the edges 22, 23 and 24 of the element 2 of a subjacent course. These relationships in the particular arrangement shown in Figure 6 produce the two different main motifs in the assembly and these relationships also produce the two different sub-motifs, namely, the diamonds and half diamonds which, in the particular arrangement of Figure 6, are in certain relations respectively to the two different main motifs. Thus the two adjacent diamonds are formed at the upper and lower sides of the motif A and the single diamond and two half diamonds are formed at the upper and lower sides of the motif B. It will also be noted that the half diamonds of the motif B form side extensions of the motif A. The assembly of Figure 6 shows a relatively simple design which is produced by the mechanical form of the strips 2 and 3, the tabs of which in each strip are not complementary to the spaces thereof, which tabs, however, are complementary to the recesses of the other strip.

Figure 9 shows an assembly of the strips illustrated in Figures 7 and 8. In this assembly only one type of the strips, namely, the strip 108, is utilized in all the courses. It will be noted that the motifs C which are produced in this assembly by the tabs and the recesses therebetween, because of the relationship of the serrated edges 30 of the tabs to the serrated edges of the recesses are all alike and have two diamonds at the upper and lower edges of the motif. This motif C is similar in general outline to the motif A of Figure 6 but is formed without the side half diamonds. 35 This modification results from the use of strips which are alike, but it also illustrates the possibility of assembling strips having the tabs thereof complementary to the recesses between the tabs to produce a motif having the characteristics of 40 the motif A, said motif A being produced by complementary strips having the tabs and recesses in each strip non-complementary. While the assembly in Figure 9 is limited to a single motif C, the assembly of Figure 6, utilizing the strips of 45 the form of Figures 2 and 3, produces two motifs of different character in the same assembly. However, in some cases it may be preferable to utilize strips or elements which are all of the same form and which are produced as shown in 50 Figure 7. The assembly of Figure 9 shows the type of result which may be obtained with such strips.

The assembly of Figure 12, like the assembly of Figure 9, shows strips all of one type in overlapping arrangement in courses. This assembly utilizes the strip 111 of Figure 11. It will be noted that the motif D produced by the tabs and the recesses therebetween is similar to the motif B of the Figure 6 but unlike the motif B has the half diamond extension at the side thereof. All 60 the motifs of the assembly of Figure 12 are alike. For the reasons discussed in connection with Figure 9 the assembly of strips all of one kind in some cases may be preferable. The assembly of 65 Figure 12 illustrates how the modification of the motifs may be obtained while utilizing strips having the form of the edges of the tabs and of the recesses as proposed by my invention, namely strips which are complementary and with tabs 70 and recesses of similar outline, the tabs being complementary to the recesses.

If the elements illustrated in Figure 8 and Figure 11 are laid in alternate courses, as is the case in the assembly of Figure 6, the edge 112 may be 75

laid to be coincident with the edge 117 of the recess in strip 111 of Figure 11. Similarly the edge 115 of the tab of the strip 111 may be laid to be coincident with the edge 114 of the recess 5 of the strip 108 of Figure 8. When such an arrangement is adopted in the assembly there may be produced motifs having serrated outlines at the top and bottom but without the formation of diamonds adjacent the top and bottom outlines 10 or at the sides. It will be noted that in this case, as in the assembly of Figure 6 there will be utilized a pair of strips to produce the desired result, the strips of said pair, however, being non-complementary to each other, as is the case in 15 the assembly of Figure 6, but each having their tabs complementary to the spaces between the tabs. The motifs formed by such an assembly which have the character provided by the serrated outlines but the edge effects produced by 20 the diamonds and half diamonds will not be obtained. Nevertheless the edges of the tabs and recesses will appear thicker and the shadow effect will be enhanced. Moreover, as will be described hereafter, variations in the laying may cause one 25 edge to be seen below the other to produce a still different effect with the parallel serrated outlines.

It will now be understood that the effects obtained in Figure 6 may be produced by a pair 30 of different strips, which may be cut at one time from a sheet with tabs non-complementary to the spaces therebetween, whereas to produce the assemblies of Figures 9 and 12, or an assembly 35 utilizing the strips 108 and 111 of Figures 8 and 11 it is necessary to cut the strips in two different operations to produce the two different strips. By using strips both of the same kind, for example strip 2 of Figure 2, I may produce 40 the same forms of the main motif as are produced by two different strips 108 and 111 as described in the previous paragraph.

Figure 13 shows an assembly of the strips illustrated in Figures 2 and 3 in which assembly the two different types of strips are arranged at 45 random as to their position in the courses and as to their position in one course with respect to another course. As may be seen from Figure 13, in the uppermost course, strips 130 and 131 of the type illustrated in Figure 3 are shown in 50 laterally adjacent arrangement in the course. In the next course beneath at the left is shown a strip 132, only one full tab of which appears in the overlapping assembly. This strip also is of the type shown in Figure 3. The edges 80, 81, 82 and 83 are coincident with the edges 70, 71, 72 and 73 of the tabs 52 and 53 of the superimposed strip 130. The edges 70, 71, 72 and 73 of the strip 132 in the second course are coincident with the edges 80, 81 and 82 of a strip 134 in the third 55 course, the strip 134 being also of the type shown in Figure 3. At the right hand of the strip 132 in the second course is shown a strip 136 of the type illustrated in Figure 2 laid in relation to the strips 130 and 131 of the uppermost course in 60 the manner shown in Figure 6. Thus there are produced the half diamonds and diamonds and motifs similar to those of Figure 6. It will be noted, however, that below the righthand tab 53 65 of the strip 130 appears a half diamond instead of a full diamond. It will be clear from the above description that this results from the coincidence of the edges 70 and 71 with the edges 80 and 81 of the strip 132. The joint between the 70 strips 132 and 136 is shown at the line 138.

It now will be seen from this figure that the arrangement above mentioned in which a strip of the type of Figure 2 is laid in laterally adjacent arrangement to the strip of Figure 3 with the rear overlapped edges 50 and 20 in alignment, 5 that a modification of the motifs in Figure 6 may be obtained. It will also be clear that where the assembly is composed of strips in successive courses all of like outline, but of the type shown in either Figures 2 or 3, the diamonds and 10 half diamonds are not developed in the assembly.

Further modifications of the motifs are evident from a mere inspection of the figure. These are obtained in some cases by laying strips which are adjacent endwise in the courses transversely out 15 of alignment. This may be accomplished, for example, by placing one strip with its rear edge 20 or 50 offset $\frac{1}{4}$ " from that of an adjacent strip in the course. Such offsets may produce for example sub-motifs composed of small diamonds 20 and half diamonds separated by the points of the serrations of the tabs of the strips. This may be seen at the lower portion of Figure 13. In some cases the offset may produce the parallel 25 positions of the lines 40, 41, 42 and 43 and the lines 30, 31, 32 and 33 or similar parallel arrangement of other edge lines. The exact modification produced depends not only upon the amount of 30 the offset, which may be varied in different cases, but also upon the direction of the transverse offset of one strip with respect to the strip in the subjacent or in superimposed course.

It will also be noted that apparently irregular motifs are produced when certain offsets are used 35 with certain combinations of these strips of Figures 2 and 3. While it will be understood that particular designs and repetition of the motifs may be accomplished by adopting a systematic arrangement of the strips in relation to each other and of the direction of the offset, if any, 40 in connection with the particular form of the strip, it is also possible to produce pleasing effects which have not the regularity and repetition of the motif which usually is experienced in assemblies of shingle strips or other covering elements. 45 The obtaining of these variations is easily accomplished with the elements of the present invention. For example, when a course of shingles is being laid and the two types of strips illustrated in Figures 2 and 3 are being used, selection may 50 be made at random from piles of each of the types of strips. This random selection alone will produce variations, as has been described above and as may be seen from Figure 13. However, if in laying the strips some strips in the courses 55 are offset transversely of the course, the variation of the sub-motifs may be obtained as well as further modification of the main motif of the assemblies.

This offset may be readily accomplished by 60 means of the laying marks referred to above. If instead of laying an element with these marks in exact coincidence with the edge 20 or 50 to be overlapped of the subjacent element, a slight offset is given merely by gauging with the eye, 65 the modifications which have been mentioned and shown may be produced. It is also to be noted that in addition to the gauging of the amount of offset which may be obtained by noting the position of the laying mark with 70 respect to the edge 50 or 20 to be overlapped of the subjacent element, the workman may gauge the element by noting the position of the tabs with respect to the edge of the recess of the subjacent element. Thus in some cases it may 75

be desirable to change the element being laid to one of another type in order to avoid immediate repetition of a motif or of a sub-motif or otherwise to modify the design and character of the assembly.

A further modification of the assemblies which are possible with the element of my invention is shown in Figure 14. In this assembly elements of the types of Figures 2 and 3 are utilized and are laid in random selection as to these types. In the assembly of Figure 14 the edges 5 and 6 of the element of the type of Figure 2, for example, or the edges 9 and 10 of the element of the type of Figure 3, are lapped upon the adjacent corresponding end edge of an element adjacent in the course. Thus the element 150, which is the type illustrated in Figure 2, has its lefthand edge 5 lapped upon the righthand edge 10 of an element of the type of Figure 3. Upon the righthand edge 6 of the element 150 is lapped the lefthand edge 5 of an element 152 laid adjacent thereto in the course. Similarly the end edges of elements in the other courses of the assembly of Figure 14 are lapped upon each other, the lap in some cases being in one direction and in other cases in another direction.

It will be noted that the amount of the lap in the particular embodiment illustrated in Figure 14 is equal to the distance in the direction of the course which corresponds to one of the lines forming the serrated edges. For example, the element 150 has its lefthand end edge 5 at the point of intersection of the lines 80 and 81 of an element 151 of the type of Figure 3. When the rear edge 20 of the element 150 is laid in alignment with the rear edge 50 of the element 151, the edges 42 and 81 may coincide. On the other hand, when the rear edge 20 of the element 150 is in alignment with the rear edge 20 of the element 152, these elements being of the same type, the edge 42 which is lapped upon the edge 41 crosses this edge to produce a small half diamond, the point adjacent the edge 42 extending over the edge 41. By lapping the edges 5 and 6 in the reverse manner the visible half diamond may be produced at the left rather than at the right of the point. The amount and direction of the endwise overlap, however, may be varied to produce further modifications and such combinations and arrangements are within the scope of the invention.

It will be noted that the lapping of the end edges of the strips in the courses may produce the effect of shifting the strip endwise in the course with respect to a subjacent or a superimposed strip. Thus between the strip 150 and the strip 155, instead of two full diamonds which would be formed by the points 34, 35 and 36 meeting the corners 88 and 89 and the notch therebetween, as in the assembly of Figure 6, there is formed a space in which the sides 30, 31, 32 and 33 are parallel to the edges 80, 81, 82 and 83. In some cases, however, it is apparent, from Figure 14, that a diamond and an open diamond may be formed, or a diamond and a half diamond as a part of the area of a given strip. Various modifications may be made by selection of the type of strip and the amount of the endwise overlap. Suitable variety of effects, however, may easily be obtainable with two strips, for example, of the types shown in Figures 2 and 3 with an amount of overlap a distance equal to one of the lines of the serration.

Moreover, while it is to be noted that, in the

particular arrangement illustrated in Figure 14, the elements are arranged with the rear edges 20 or 50 to be overlapped in alignment, further modification of the effects shown in Figure 14 may be accomplished by laying the elements with a transverse offset as described above in connection with Figure 13. It will further be noted that with the serrated edge a convenient guide is at hand in laying the elements to determine the amount of endwise overlap, it being merely necessary to bring the overlapping edge, for example the edge 5, in alignment with a point of the serration. Neither in connection with the assembly of Figure 13 nor that of Figure 14 is it necessary to adopt a strict and rigid arrangement by measurement. In fact more pleasing effects are produced by slight irregularity in the arrangement which may be accomplished in the manner described above by the workman merely using the laying guides 25 and 65 and the points of serrations. All such variations are within the scope of my invention.

In Figures 4 and 5, which show two strips which are complementary to each other and cut in the manner illustrated in Figure 1 transversely across the strips, the strips are provided with bands 160 to 165 inclusive of different widths. These bands may be of different colors. It will be noted that as a result of the complementary method of cutting the two strips the colors on one strip proceed in the reverse order from left to right than in the other strip. It will also be noted that as a result of forming in the sheet 1, the transverse cuts which connect the serrated outlines with the longitudinal edge of the sheet, these cuts being made in offset arrangement lengthwise of the sheet, the colors assembled on the strip of Figure 4 are not merely different by being reversed from those of Figure 5, as the offset of the transverse cut develops a different order in the two strips.

The color bands 160 to 165 may be applied to the strip in various ways. For example, when strips of slate surfaced roofing are to be made the color bands may be applied by suitable means transversely of the sheet 1 in sections or areas of different width longitudinally of sheet 1. By another method of producing the strips of Figures 4 and 5 the color bands may be applied as longitudinal bands extending throughout a sheet 1 and in laterally adjacent arrangement across the sheet. It would then be necessary to cut the strips of Figures 4 and 5, in the serrated outlines, producing the tabs and recesses, transversely of the length of the sheet 1. This transverse cut of serrated outline, however, may be formed so as to produce two complementary strips. In such case, when it is desired to avoid waste of the material, complementary strips of the type shown in Figures 2 and 5 may be produced at the same time or complementary strips of the type of Figures 3 and 4 may be simultaneously produced. The transverse cuts then extend completely across the sheet 1. Color bands shown in connection with Figures 4 and 5 can as well be utilized in the strips shown in the other figures, the complementary cutting operation producing the reversal of the color bands in the two strips and the offsetting of the transverse cuts to form the ends of the strips still further modifying the arrangement of the colors upon the two strips regardless of the particular character of the outline of the edge of the strip.

The width of the color bands illustrated in Figures 4 and 5 has been made to correspond to one

or more of the portions of the serrated outline. While this arrangement may be preferable in many cases, the invention is not limited to the coincidence between the division line between the 5 color bands with the points of the serrated outlines, it being possible to obtain the variation in the arrangement of the colors upon the strips by reversal of the complementary strips as has been described above, whether or not the width of the 10 color bands is that determined by the lines of the serrations. The arrangement shown in Figures 4 and 5 is merely typical and has been shown in these particular figures for the sake of convenience and simplicity of illustration. The variations illustrated in Figures 4 and 5 may be used to obtain further modification of the effects produced in the assemblies shown in Figures 6, 9, 12, 15 13 and 14.

What is claimed as new is:

20 1. A pair of covering elements each having a tab projecting from the body thereof, the outer edge of said tab on each element having a serrated outline, said edge of the tab on one element being of complementary outline to said edge of 25 the tab of the other element, the portion of the edge of the body of each element adjacent its tab having a serrated outline complementary to that of the tab of the other element.

2. A pair of covering elements each having a 30 plurality of tabs projecting from the body thereof and separated by a recess of similar dimension to the tabs, the tabs on one element being complementary to the recess of the other element and having their outer edges of serrated outline non- 35 complementary to the outline of the inner boundary of the recess between the tabs on the same element.

3. A pair of covering elements in the form of 40 strips each having tabs projecting from the body thereof and having the lengthwise portions of the edges of the strip of serrated outline, the strips of said pair being of like form except that in the respective portions of said lengthwise edges the serrations of one strip are complementary to 45 those of the other strip.

4. An assembly of elements each having a tab and a recess adjacent to said tab, the outer edge of said tab and the inner edge of said recess being of similar serrated outline, at least some of 50 said elements being assembled in pairs in overlapping arrangement with the points of the serrations of the tabs meeting the points of the notches of the recesses, the elements of said pair being of like form except that like portions of 55 said pair of elements have the edges thereof respectively complementary.

5. An assembly of elements each having a tab and a recess adjacent to said tab, the outer edge of said tab and the inner edge of said recess being 60 of similar serrated outline, said elements being assembled in overlapping arrangement with points of the serrations of the overlapping tabs meeting points of the notches of the recesses, said serrated outlines of said tabs and recesses in the 65 same element being non-complementary.

6. An assembly comprising a pair of elements having the edges to be exposed thereof formed in

complementary outlines and with the tabs of one element complementary to recesses in the other element, the tabs of each element being generally similar to each other but being non-complementary to the recesses of the same element, said elements being assembled in overlapping arrangement with the edges to be exposed of the overlapping tabs adjacent the inner edges of the recess of the other elements. 5

7. An assembly comprising a pair of elements 10 having the edges to be exposed thereof formed in complementary outlines with the edge of a tab of one element in complementary serrated outline to a recess in the other element but with the tab of each element non-complementary to the recesses of the same element, said elements being assembled as in courses in overlapping arrangement with the edge to be exposed of the overlapping tab adjacent the edge of the recess of the other element, and with the points of the serrations of the tab and of the recess in a relation determined by the offset transversely of the course of the element in one course with respect to the element in an adjacent course. 20

8. An assembly comprising a pair of elements 25 having the edges to be exposed thereof formed in complementary outlines with the edge of a tab of one element in complementary serrated outline to a recess in the other element but with the tab of each element non-complementary to 30 the recesses of the same element, said elements being assembled as in courses in overlapping arrangement with the edge to be exposed of the overlapping tab adjacent the edge of the recess of the other element and with the points of the serrations of the tabs and of the recess in a predetermined relation in the direction of the course 35 with respect to the points of the serrations of an element in the adjacent course, said elements being overlapped endwise in the courses upon 40 elements adjacent thereto in the course.

9. An assembly of covering elements comprising a plurality of courses of the elements in overlapping arrangement, the elements being laid 45 adjacent to each other endwise in the courses, each of said elements having a tab with a recess adjacent thereto, the tabs of said elements having an outline similar to the recess of the same element but not complementary thereto, some of 50 the elements of said assembly having an outline complementary to the outlines of other elements of the assembly, said elements being arranged in the assembly at random with respect to the two kinds of elements but with the edges of the overlapping tabs adjacent the edges of the recesses 55 in the elements of the adjacent course overlapped thereby.

10. A pair of covering elements each having a tab projecting from the body thereof, the outer edge of said tab on one element being of complementary outline to that of the outer edge of the tab of the other element, the portion of the edge of the body of the element adjacent the tab in the same element being of similar extent to that 60 of said tab but being of non-complementary outline to that of said tab in the same element. 65

JOHN A. TOPPING.
